FOREIGN PATENT DOCUMENTS

GB 23165263 B * 3/1997 ..... H01Q 1/245

Primary Examiner — Karen E Eldridge Powers*(74) Attorney, Agent, or Firm* — Lennie A. Bersh(57) **CLAIM**

The ornamental design for a hairbrush, as shown and described.

DESCRIPTION

FIG. 1 is a front right perspective view of a hairbrush showing my new design;

FIG. 2 is a rear perspective view of the hairbrush shown in FIG. 1 with a pop socket in a closed position;

FIG. 3 is a rear perspective view of the hairbrush shown in FIG. 1 with a pop socket in an open position;

FIG. 4 is a front elevation view of the hairbrush shown in FIG. 1;

FIG. 5 is a rear elevation view of the hairbrush shown in FIG. 1;

FIG. 6 is a left side elevation view of the hairbrush shown in FIG. 1;

FIG. 7 is a right side elevation view of the hairbrush shown in FIG. 1;

FIG. 8 is a top plan view of the hairbrush shown in FIG. 1; and,

FIG. 9 is a bottom plan view of the hairbrush shown in FIG. 1.

The broken lines in FIGS. 1-9 illustrate portions of the hairbrush that form no part of the claimed design. The dash-dot-dash broken lines in FIGS. 1-7 illustrate the boundary of the claimed design which forms no part thereof.

1 Claim, 6 Drawing Sheets(56)
